(57) **CLAIM**

The ornamental design for a pot lid holder, as shown and described.

DESCRIPTION

FIG. 1 is a front, top perspective view of a pot lid holder, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and

FIG. 8 is a bottom plan view thereof; and,

FIG. 9 is an exploded front perspective view thereof.

The broken lines show portions of the pot lid holder that form no part of the claimed design.

The dashed lines in the figures illustrate portions of the pot lid holder that form no part of the claimed design.

1 Claim, 9 Drawing Sheets
